By Messrs. A. G. Wilson & Co., Attoys.

UNITED STATES PATENT OFFICE.

CHARLES J. DUNBAR, OF KALAMAZOO, MICHIGAN.

BINDER.

1,405,303.

Specification of Letters Patent.

Patented Jan. 31, 1922.

Application filed October 4, 1920. Serial No. 414,390.

To all whom it may concern:

Be it known that I, CHARLES J. DUNBAR, a citizen of the United States, and resident of Kalamazoo, in the county of Kalamazoo and State of Michigan, have invented certain new and useful Improvements in a Binder, of which the following is a specification.

My invention relates to binders and particularly to an improvement in the method of mounting posts in the top and bottom members of the binder.

An object of my invention is to provide a binder construction in which the objections to the sectional posts heretofore employed are eliminated. In the sectional post constructions it is well known that the posts are usually joined by screw connections, additions to or subtractions from the length of the post being secured by adding or removing screw threaded sections of the post. In attempting to remove an outer section of a screw threaded post it frequently happens that other sections are unscrewed instead of the one desired and difficulty is sometimes experienced in separating the sections thus removed. In my construction I provide single one-piece posts of graduated length and mount the posts in the binder frame or base by a bayonet joint. When a different length of post is to be applied it is a simple operation to remove the one-piece post and replace it by another of the proper length.

Another object of the invention is to provide means in the top member of the binder for securely engaging the posts and providing for considerable variation of length of posts without varying the gripping capacity. The desired result is secured by providing a block having a through aperture of substantially the size of the post and mounting the locking element near the lower end thereof. Thus the post will be securely gripped without the possibility of twisting or canting.

The invention will be more readily understood by reference to the accompanying, in which,

Fig. 1 is a sectional view showing a binder constructed in accordance with my invention;

Fig. 2 is a view of a slightly modified form of a bayonet joint connection;

Fig. 3 is a sectional view on the line 3—3 of Fig. 1;

Fig. 4 is a sectional view on the line 4—4 of Fig. 1;

Figs. 5, 6 and 7 are views of different lengths of posts adapted to be employed;

Fig. 8 is a view of a modified form of posts; and,

Fig. 9 is a sectional view through a modified form of block such as I prefer to employ.

In the drawings it will be seen that I provide bottom and top frame members 10, 11. Mounted in the bottom or base member 10 are blocks 12, 13 of duplicate construction, each having a socket for the reception of posts 14, these sockets being wholly within the limits of the base as distinct from construction in which a stub projects above the base. In the socket I provide communicating vertical and horizontal slots 15, 16, respectively, adapted to cooperate with a pin 17 projecting from the post 14. As shown in Figs. 5, 6 and 7, posts of different lengths may be employed, these being of one piece and thereby avoiding the objections to sectional posts such as heretofore employed. By employing one-piece posts there is no possibility of disengagement after they are locked as will occur if a similar form of connection is provided in a sectional post.

In the upper frame member or top 11 I provide similar blocks 18 each having through apertures 19 therein which are of substantially the size of the posts. A transverse slot is provided near the lower surface of the blocks and in the slot I mount a locking bar 20 adapted to be actuated by a screw 21 in the usual manner. It will be seen that because of the nature of the apertures in the blocks 18 the post is allowed considerable freedom of movement. It may protrude, if desired, but if a non-protruding post is wanted such a construction is provided for; and, furthermore, posts may have considerable latitude of vertical movement without missing the locking bar. In the construction shown in Figs. 1 and 2 the blocks are shown as of solid construction, but in the construction of Fig. 9 I have shown a modification in which the block is composed of two parts 22, 23 joined by rivets 24.

In the modified form shown in Fig. 2 the upper frame member remains the same, but the blocks and the post connection are slightly different. The blocks 25 in the base are recessed and have an inwardly projecting pin 26. The posts 27, as shown in Fig. 8, are provided with a bayonet slot 28 adapted

to engage with the pin. Otherwise the construction remains the same as that heretofore described.

Obviously the construction herein illustrated is capable of much modification and I do not wish to be limited except as indicated in the appended claims.

I claim:

1. In a binder, the combination of base and top members, said base member having a socket wholly within the limits of the member, a plurality of one-piece posts of varying lengths and of uniform effective diameter, and means providing a bayonet joint connection between a selected post and the socket in said base member.

2. In a binder, the combination of base and top members, said base member having a socket wholly within the limits of the member, a plurality of one-piece posts of varying lengths and of uniform effective diameter, means providing a bayonet joint connection between a selected post and the socket in said base member, said top member being of substantial thickness and having through openings for the reception of the posts, and a locking bar within said top member and located near the lower edge thereof for engaging and holding said posts.

Signed at Chicago, Ill., this 2nd day of 30 October, 1920.

CHARLES J. DUNBAR.
